Henry Webber
Cheese Patent

The Schedule referred to in this Specified Patent and making part of the same, containing a description in the words of the said Henry Webber himself of his improvement in a machine for turning & curing cheese.

To all to whom these presents shall come, Be it known that I Henry Webber of Richfield in the County of Otsego and State of New York have invented a new and useful semi-Revolving Cheese shelf and that the following is a full & exact description thereof. The semi revolving cheese shelves consist of a frame into which double shelves are placed. The frame is made of three distinct frames put together the centre frame being as wide as the two outside ones. The elect on which the shelves rest run parallel with each other across the frames to which the shelves are fastened the one the upper side & the other the lower side alternately. One half the shelves are nailed or fastened to the outside frames the other to the inside frame which is shorter than the outside frame, and is raised (with the shelves attached to it together with the cheese on the same) by a wooden post until the cheese touch the shelves above them which are fastened to the outside frames. When the whole is ready for turning, which is done by a shaft or axle passing through the centre of the frame and is supported by strong posts placed permanent in the cheese house; In order to have the centre frame (with its shelves) move the shaft or axle (on which the whole rests & turns) passes through a plank or cross-bar fastened to the outside frames with a mortice in the centre frame which leaves it free to move up or down by windlasses placed at top and bottom end of the frame. By the above process the cheese are easily compressed between the shelves the frame being either end up. The frame turns half round and to prevent the cheese from sliding out while turning slats are fastened to the back of the frame & shelves which may be made supports for the shelves & frame when necessary. Two more slats may be placed in front (in the centre) as supports. The first slab is fastened to the 1st o.

3.5 th 8c (shelves,) the second is fastened to 2.7 to 4.6 to 8c and to the frame at top & bottom. Now what I claim as my own invention and not previously known is the principle of comprising the cheese for turning between two series of shelves one stationary and the other moveable in the manner herein set forth and also the right of varying the same as to produce similar results by analogous means.
